4 Claims. (Cl. 34—99)

This invention relates to hairdryer hoods.

The hairdryer hood commonly used by hair-dressers comprises a hood top and an integral metal drying chamber to form a finger hood respectively a whirlwind hood with direct or indirect hot air guideways. Such bulky appliances of high weight which are adjustably mounted on a stand can only be used for commercial purposes as e.g. in hairdresser shops.

For domestic purposes on the other hand hairdryer hoods are known which e.g. consist of an air-fed bag, which by means of ribbons may be tightly secured at the forehead and in the neck. The airtight fastening of the hood from the forehead to the neck is very inconvenient and troublesome and in addition when handling the hood the hair style is easily upset by the direct admission of the air flow. Also a non-uniform drying effect occurs.

With respect to such drawbacks one object of the invention is to provide a hairdryer hood which also as domestic appliance may meet the requirements for a satisfactory air flow and for a uniform drying effect. The invention resides in the provision of a hairdryer hood, the top of which is provided with a drying chamber consisting of interconnected collapsible wall elements which in uncollapsed position form a bell-shaped hood for receiving and guiding the air flow.

The top of the hood may be designed as a cavity for admission and distribution of the drying air, or such cavity may receive a ventilator set with the necessary motor and the heater elements.

The collapsible wall elements for feeding and guiding the air and for forming the drying chamber may be differently designed.

According to the preferred embodiment the drying chamber comprises interconnected slightly tapered concentric rings which in extended position form the hood jacket.

The top of the hood is provided with suitable means for suspending or setting up as e.g. a carrier arm or the like, so designed that the drying chamber in its working position may easily receive the woman's hair to be dried.

The accompanying drawings illustrate one embodiment of the invention, constructed according to the best mode so far devised for the practical application of the principles thereof, and in which:

FIG. 1 is an elevation and partial section of a dryer hood consisting of a plurality of ring elements in working position,

FIG. 2 is an elevation and partial section of the dryer hood according to FIG. 1 in non-operating position.

In the drawings reference number 10 refers to the top of the hood, reference number 11 to the air intake and reference number 12 to the bell-shaped drying chamber.

In FIGS. 1 and 2 the top member 10 of the hood is provided with a ventilator appliance consisting of air circulating means here shown as an electric motor 30 and driven ventilator wings 31 located in a space defined by an inner annulus or ring 51 extending downwardly from the top member. When using the ventilator the air enters via the air inlet 11 and/or via the air inlet opening 32, adjacent to air heater means 33. An electric switch 50 preferably has three switching positions.

2

The drying chamber 12 consists of a series of annular substantially rigid frusto-conical elements here shown as concentric rings 51, 52, 53, 54, 55, the diameters of which slightly increase from top to base of the hood. 5 The outermost ring 55 is provided with an inwardly curved edge portion. As seen from FIG. 2 the rings 51 to 54 may be put into the annular space 56 of top 10. For this purpose the top 10 of the hood is provided with a projecting ring or outer annulus 57 which at its free edge may be provided with locking means 58 for the outermost ring 55 and which defines between itself and the inner annulus 51 a storage space for receiving the rings. In collapsed condition the whole appliance has the appearance of a disk-like body which at 15 its one surface is closed by the screen 46 with the inwardly curved ring 55 bridging the annular storage space 56. The telescoping ring elements 51 to 54 in a manner known per se may be provided with special stops and abutments and also may at their inner faces have air guiding members 59.

The top of the hood 10 is provided with mounting means 60 as e.g. a holding arm, a holding clamp, a suspension arm or the like, for facilitating the putting up of the dryer hood in convenient operating condition.

25 The top 10 of the hood may be provided with a ventilator appliance. On the other hand it is likewise possible to provide the hood with means for admitting air from a separate air source, e.g. the air may be supplied by a vacuum cleaner.

30 All structural elements of the dryer hood, except the motor may consist of heat resistant synthetic materials.

The telescoping rings 51 to 54 respectively the top 10 and the outer edge 55 according to FIG. 1 consist of solid heat-resistant synthetic materials respectively completely 35 or partly of metal.

40 A hairdryer hood according to the present invention enables an air flow comparable with that of the so-called whirlwind hoods. The hair with the desired hair style is uniformly dried. An upsetting of the hair is not possible. So also in a household the same desired results are attainable which up to now only were obtainable with the commercially used bulky appliances of hairdressers. The production from synthetic material leads to a very nice and convenient appliance. The hood jacket has to be designed such that the head of the 45 woman may easily be brought into the desired position with respect to the top of the hood.

What I claim as my invention is:

1. A collapsible and expandable hair-drying hood comprising, in combination, a top member including an outer annulus and an inner annulus defining a storage space therebetween and extending downwardly from said top member; a series of annular substantially rigid frusto-conical elements telescopically movable with respect to the inner annulus and with respect to each other between a collapsed position within said storage space and an expanded position, said series including a first element movable over said inner annulus and a last element having a lower end with the cross-section of said elements increasing from the first to the last element, said first element being releasably engageable with said inner annulus and all of said elements being releasably engageable with each other for holding said elements in said expanded position, said top member and said inner annulus thereof forming together with said elements in expanded position a drying chamber, said lower end of said last annular element being provided with an inwardly extending edge portion bridging said storage space at the lower end thereof when said elements are collapsed to form with the inner and outer annulus a closed storage chamber for receiving the collapsed elements therein; air inlet means communicating with the interior of said

inner annulus; air circulating means; and an air heater, said air circulating means and said air heater being mounted in said top member within the space defined by said inner annulus.

2. A collapsible and expandable hair-drying hood comprising, in combination, a top member including an outer annulus and an inner annulus defining a storage space therebetween and extending downwardly from said top member; a series of annular substantially rigid frusto-conical elements telescopically movable with respect to the inner annulus and with respect to each other between a collapsed position within said storage space and an expanded position, said series including a first element movable over said inner annulus and a last element having a lower end with the cross-sections of said elements increasing from the first to the last element, said first element being releasably engagable with said inner annulus and all of said elements being releasably engageable with each other for holding said elements in said expanded position, said top member and said inner annulus thereof forming together with said elements in expanded position a drying chamber; an annular member telescopically connected to said lower end of said last annular element and having an upper edge portion of a diameter substantially equal to that of said outer annulus and an inwardly extending curved lower edge portion bridging said storage space at the lower end thereof when said elements are collapsed, said annular member forming with the inner and outer annulus a closed storage chamber for receiving the collapsed ele- 20 25 30

ments therein; cooperating means on said upper edge portion of said annular member and on a lower edge portion of said outer annulus for releasably holding said annular member on said outer annulus when said annular elements are in the collapsed position; air inlet means communicating with the interior of said inner annulus; air circulating means; and an air heater, said air circulating means and said air heater being mounted in said top member within the space defined by said inner annulus.

3. A hair-drying hood as set forth in claim 1, wherein air-guiding vanes are provided on the internal surfaces of said annular frusto-conical elements.

4. A hair-drying hood as set forth in claim 1, including a screen attached to the lower edge of said inner annulus to enclose the space encompassed by said inner annulus.
